UNITED STATES PATENT OFFICE.

LEMI B. DENTON, OF GRAND RAPIDS, MICHIGAN, ASSIGNOR OF ONE-HALF
TO ORIN A. WARD, OF SAME PLACE.

DESIGN FOR A BLANK FOR CASTER-CASES.

SPECIFICATION forming part of Design No. 26,112, dated September 29, 1896.

Application filed February 27, 1896. Serial No. 581,077. Term of patent 7 years.

To all whom it may concern:

Be it known that I, LEMI B. DENTON, a citizen of the United States, residing at Grand Rapids, in the county of Kent and State of Michigan, have invented and produced a new and original Design for Tube-Blanks from which Caster-Cases are Made, of which the following is a specification, reference being had to the accompanying drawing, showing a part thereof.

The figure in the accompanying drawing shows an elevation of the blank tube and dotted outlines of the sheet of metal from which it is formed, the blank tube and the outline being deemed necessary to fully illustrate the design.

The body of the blank tube between the lines *a a* and *x x* should be of uniform size,

and the fingers *B*, retaining the same tubular form, should incline inward toward the top, ²⁰ as shown, so that the circle at the top of the fingers is somewhat smaller than at the line *x x*.

The upper end of the case is open, so that the fingers are free to spring, as necessary, to receive and retain the pintle.

What I claim as new is—

The design for a tube-blank for castor-cases as shown and described.

Signed at Grand Rapids, Michigan, February 19, 1896.

LEMI B. DENTON.

In presence of—

I. J. CILLEY,
BYRON E. PARKS.
